UNITED STATES PATENT OFFICE.

FREDERICK MARBLE, JR., OF ONEIDA, NEW YORK.

RAILWAY-GATE.

SPECIFICATION forming part of Letters Patent No. 352,334, dated November 9, 1886.

Application filed July 9, 1885 Serial No. 171,103. (No model.)

To all whom it may concern:

Be it known that I, FREDERICK MARBLE, Jr., of Oneida, in the county of Madison, in the State of New York, have invented new and 5 useful Improvements in Railway-Gates, of which the following, taken in connection with the accompanying drawings, is a full, clear, and exact description.

This invention consists in improved means 10 for automatically closing and opening the gates of railway-crossings by the approach of the engine or train.

In the annexed drawings, Figure I is an elevation of my invention, taken at the side of 15 the railway. Fig. II is a vertical section of the same. Figs. III and IV are enlarged detached views of the rear side of the devices, which are arranged near the track to be actuated by the passing train and transmit motion to the bell and gate, respectively. Fig. V is an enlarged detached view of the devices 20 for retaining the gate in its closed position, taken in a plane at right angles to that of Fig. I. Fig. VI is a plan view of the plate which 25 sustains the upper end of the plunger. Fig. VII is a detail view of the yielding platform, which is arranged between the two gates to raise the same automatically in case a horse 30 is caught between said gates; and Fig. VIII is a plan view showing more clearly the arrangement of the ropes and pulleys by which motion is transmitted from the plungers at the 35 side of the track to the gate.

Similar letters of reference indicate corresponding parts.

R denotes the railway-track, and A one of the gates arranged at opposite sides of said track in a road crossing the said railway. This gate is arranged to slide vertically on 40 posts C C, and is counterbalanced by weights v v, connected to the ends of ropes or chains b b, which pass over pulleys pivoted to the top of the posts, and are attached at their opposite ends to the gate, the weights v v being 45 sufficiently heavy to draw the gate to its elevated position.

d is a plunger, which slides on a vertical guide-plate, w, secured to a rigid frame or post underneath the track. The foot of said plunger is provided with a cylindrical shank, which 50 passes through an eye in a lug, w', on the base

of the plate w, a spring, e, interposed between the said lug and foot of the plunger serving to yieldingly sustain the plunger in an elevated position. To the upper end of the said plunger is pivoted an arm, d', which passes through a slot, h', in a plate, h, firmly secured to a suitable support at the inner side of the rail R, as represented in Fig. VI of the drawings, the slot h' being long enough to allow the upper end 55 of the arm d' to swing below the top of the rail. A weight, g', is connected with the arm d' in such a manner as normally to sustain it in an erect position. On the plate w is journaled a drum, D, and to the shaft of said drum 60 is attached a ratchet-wheel, g, as best seen in Fig. IV of the drawings.

On the plunger is a pawl, f, which engages the ratchet g, and imparts rotary motion to the same when the plunger d descends. Two ropes 70 or chains, b b, are connected to the drum D, and extend from thence around sheaves a a', journaled to the posts C C beneath the gate, as shown in Fig. II of the drawings, and from thence, the aforesaid ropes or chains are 75 extended to and connected with the gate A. The described plunger d is arranged a proper distance from the road-crossing to allow a horse ample time to cross the railway and pass out of the gate before a locomotive or train 80 running at high speed can reach the road-crossing. As the locomotive passes over the arm d' of the plunger d, it depresses the latter, and thereby imparts rotary motion to the drum D, as before described. In the rotation of said 85 drum the ropes or chains b b are wound up on the drum, and are thereby caused to draw down the gate A into its closed position. One of the ropes or chains b is wound around or connected with the sheave a', so as to have a 90 firm hold thereon, and to this sheave is attached a ratchet, c. On the post C is pivoted a pawl, k, which is weighted so as to automatically engage the ratchet c, and thereby retain the gate in its closed position. At the side of 95 the rail R, a suitable distance from the road-crossing and in the opposite direction from that of the location of the plunger d d', is arranged another plunger, m, which slides in a vertical guide-plate, w', firmly secured to a post 100 under the track, and is sustained yieldingly with its upper end nearly on a level with the

top of the rail by a spring, e' , forcing said plunger upward. On the plate w^3 is pivoted an elbow-lever, $n\ n'$, having the arm n' connected with the plunger m . To the other arm 5 of said lever is connected a rope or chain, b' , which is extended to and connected with one of the arms of a cranked lever, l , pivoted to the post C above the pawl k . The other arm, l' , of said lever presses on the pawl k above the 10 fulcrum thereof, so that when a draft is exerted on the rope or chain b' the lever l is caused to throw the aforesaid pawl out of engagement with the ratchet e , and when this is effected the gate A is drawn up into its open position by the weights $v\ v$. Consequently when 15 the locomotive or train passes over the plunger m and depresses the same the gate A automatically rises to its open position.

In order to guard against the catching of a 20 horse or team between the gates after they are closed, I arrange in the road-crossing between the two gates a platform, P , supported on springs $t\ t$, so as to allow said platform to settle when stepped on by the horse. To this 25 platform I attach a downward-projecting stirrup, u , arranged in position for pressing the arm l' of the lever l against the pawl k . When the said platform is depressed, the pressure of the arm l' on the pawl k throws the latter out 30 of engagement with the ratchet e , and thus causes the gate to rise to its open position, to allow the horse or team to escape from the track.

p denotes another plunger, arranged at the 35 side of the rail R at a proper distance (say one thousand feet) from the road-crossing, and sustained in a vertical position, and with its upper end nearly or quite on a level with the rail, by a guide-plate, w^4 , and spring e' , similar to 40 those which support the plunger m , hereinbefore described.

On the plate w^4 is pivoted a sector, q , and to the axis of said sector is rigidly attached an arm, s , which is connected with the plunger, 45 so that by depressing the latter an oscillatory movement is imparted to the sector. The segmental face of the sector is grooved, and in the groove lies a rope or light chain, r , which is at one end secured to the sector q , and is 50 thence extended over a pulley pivoted to the upper end of a post, F , erected at the side of the railway, from which pulley the rope or chain is extended to a bell, B , arranged at the road-crossing. In the passage of a locomotive 55 or train over the plunger p the latter is de-

pressed and caused to impart oscillatory movement to the sector q , and this rings the bell B by means of the rope or chain r . Thus persons approaching the railway are put on guard by the signal of the bell before the locomotive 60 reaches a dangerous proximity to the road-crossing.

Having described my invention, what I claim as new, and desire to secure by Letters Patent, is—

1. In combination with the counterbalanced gate, the sheaves $a\ a'$ under the gate, the drum D , ropes or chains $b\ b$, extending from the drum around the sheaves and to the gate, the ratchet g , attached to the shaft of said drum, 70 the plunger d , sustained in its elevated position by the spring e , the pawl f , connected to the plunger, the plate h , arranged at the side of the rail R and provided with the guide-slot h' , and the arm d' , pivoted on the plunger 75 and projecting through the slotted plate h , and held normally erect by the counter-weight g' , substantially as described and shown.

2. In combination with the counterbalanced gate A , sheaves $a\ a'$, drum D , ropes or chains $b\ b$, extending from the drum to the gate, one of which is wound around the sheave a' , the arm d' , and mechanism for transmitting motion from said arm to the drum, as set forth, the ratchet e , attached to the sheave a' , the 80 pawl k , the lever $l\ l'$, engaging said pawl, the spring-sustained plunger m , the lever n , having the arm n' connected with the plunger, and the rope or chain b' , connecting the lever n with the lever l , substantially as set forth and 90 shown.

3. In combination with the overbalanced gate, the sheave a' , rope or chain b , wound on said sheave and connected with the gate, the ratchet e , attached to the sheave a' , the pawl k , the platform P , mounted on springs t , and the stirrup u , for transmitting motion from the platform to the pawl k , to throw the latter out of engagement with the ratchet, substantially 95 as and for the purpose specified.

In testimony whereof I have hereunto signed my name and affixed my seal, in the presence of two attesting witnesses, at Oneida, in the county of Madison, in the State of New York, this 6th day of July, 1885.
